UNITED STATES PATENT OFFICE

144,588

DESIGN FOR A TOY SHOVEL

David G. Samuels, Jr., Bethlehem, Pa.

Application May 16, 1945, Serial No. 119,571

Term of patent 3½ years

(Cl. D34—15)

To all whom it may concern:

Be it known that I, David G. Samuels, Jr., a citizen of the United States, residing at Bethlehem, in the county of Northampton and State of Pennsylvania, have invented a new, original, and ornamental Design for Toy Shovels, of which the following is a specification, reference being had to the accompanying drawing, forming a part thereof.

The figure is a perspective view of a toy shovel, showing my new design.

The appearance of the opposite side of the toy shovel is the same as that of the side shown except that a crank for the windlass does not appear on the opposite side.

I claim:

The ornamental design for a toy shovel, as shown and described.
